RUG

Stanley E. Waite, Oshkosh, Wis., assignor to
 Waite Carpet Company, Oshkosh, Wis., a corporation of Wisconsin

Application March 13, 1939, Serial No. 261,506

1 Claim. (Cl. 2—278)

The rug of the present invention is preferably of the tufted type in which lines of tuft stitching are passed through a backing of canvas or similar fabric and are cut to afford a pile surface. Since rugs of this character must be sewn by hand on a tufting machine, it has been found desirable in certain cases to make up the rug in sections, each of which is individually tufted and which sections are afterwards stitched together at their meeting edges. This method enables the relatively small sections to be easily manipulated by the operator on the tufting machine which would be difficult or impossible if it were attempted to manipulate the entire rug during the tufting operation especially where pattern designs of irregular contour are involved and where it is necessary to feed the backing at various angles or in various directions to secure the intended pattern effect. Although the stitching together of unit sections avoids the difficulty in manipulation of an entire rug during the tufting operation, the resultant effect in the completed rug is frequently objectionable in view of the fact that the stitching lines at the joints break through the pattern or through the plain surface of the rug so that they are easily visible and mar the appearance of the rug to a very marked degree.

The object of the present invention is to provide unit sections so configured as to effectively conceal the stitched joints and provide a continuity in the pattern effect so that the completed rug will be indistinguishable in appearance from one which is integrally formed without joint stitching.

Further objects and details will appear from a description of the invention in conjunction with the accompanying drawing, wherein—

Figure 1 is a view of a complete rug consisting of six units stitched together;

Fig. 2 is an enlarged view of one of the sections; and

Fig. 3 is a sectional view taken through line 3—3 of Fig. 1.

Each unit section A consists of a backing B of canvas or similar heavy fabric through which are stitched the lines of tuft stitching C to afford a low pile surface D of the usual character. At suitable intervals, the tuft stitching is elongated to afford elevated lines or areas of high pile E which stand up in relief from the low pile to afford a suitable pattern effect which in the present instance consists of ribs or lines intersecting to afford what may be termed a pattern unit of the character displayed in Fig. 2.

The pattern unit in the present instance is subdivided by intersecting cross ribs E' into four corner sections, each of which displays a quarter of the complete pattern unit. Along two intersecting edges of the rug full width border ribs E² are formed, while along the remaining two edges half width border ribs E³ are formed.

Each rug unit section, therefore, presents in itself a complete pattern unit and also presents 10 the corner constituents of identical pattern units which may be built up by the joining of the unit sections together as indicated in Fig. 1.

The union of the sections is effected by joint stitching F and by bringing together the half width border ribs E³ in assembling the sections, a full width high pile rib will be presented which effectively conceals the joint stitching and in character and width matches perfectly with the full width high pile ribs running through the

15 pattern sections so that not only is the joint concealed by the high pile in the contiguous edges but also by maintaining the continuity of the pattern effect throughout all portions of the rug.

20 25 For purposes of illustration, a rug has been shown which is only two sections wide so that in each of the sections it is desirable to provide two edge ribs E² of full width and two edge ribs E³ of half width since the full width ribs are

30 necessary to afford the border effect around the corners, but it will be noted that the complete rug is three sections in length so that the intermediate sections will have three edges with half width high pile ribbing and one edge only with full width high pile ribbing.

35 In like manner, if the rug were of a width to completely enclose certain sections, the interior sections would on all of their edges have the half width ribbing for the purpose of union with contiguous edges of other sections likewise provided with ribs of half width.

40 45 The object in each case is to maintain the continuity of the pattern by providing ribbing at the meeting edges of same width as the ribbing through the pattern sections so that it will be impossible to distinguish the joints or to distinguish between pattern units lying exclusively within a single unit section and pattern units made up by the combining of the corner constituents of four contiguous unit sections.

50 It will be observed in Fig. 1 that the pattern unit displayed in the upper center of the rug which is made up of the corner constituents of four unit rug sections is identical in the arrangement of the ribbing with each of the patterns indi-

vidually displayed by the units themselves so that the pattern continuity of the rug is everywhere maintained. For purposes of illustration, the joint divisions are indicated by dotted lines, but in the actual rug the stitching will be completely concealed at the joints so that the rug as a whole will present the appearance of an integrally formed rug.

It will of course be understood that the particular pattern here shown serves merely to illustrate the principles involved and that the essential feature of the invention lies in the use of the high pile edge tufting, which serves not only to conceal the seam or joint between rug sections by reason of the depth of the pile, but also by so disposing the edge ribbing that when the sections are united the pattern effect along the united edges will harmonize and maintain continuity with the pattern displayed by the individual rug sections, thus harmonizing every portion of the rug unit in a unified structure indistinguishable from an integrally formed unit.

By the use of unit sections made according to the principles of the present invention it is possible to build up complete rugs to varying sizes but all displaying the same pattern constituents, so that large and small rugs displaying the same pattern unit may be provided in cases where the furnishing of a house requires the use of harmonized rugs of different sizes. Moreover, by building a rug up in sections in the manner described, there is practically no limit to the size to which the rug may be extended, since it will consist simply in a multiplication of the individual units all so correlated as to maintain a harmonized pattern throughout.

Although the present invention relates pri-

marily to tufted rugs of the general character described, the principles here involved may be employed in connection with rug sections otherwise formed to display high and low pile areas, so that unless otherwise indicated in the claim it is not the intention to limit the invention solely to rugs formed by a tufting operation.

I claim:

A rug comprising of at least four rectangular unit sections of equal size and affording the four corners of the rug and meeting at a center point and united along their contiguous edges by stitching, each rug section having a ground afforded by low pile tufting and having in each case the same pattern unit afforded by upstanding ribs of high pile tufting, each section also having around its entire border and as a constituent of the pattern unit a rib of high pile tufting, and said border tufting along the meeting edges in conjunction affording high pile ribs adapted to conceal the stitching and equal in width with the marginal high pile border ribs of the section pattern units, said pattern units and border tufting cooperating in such a way that the individual pattern unit of each section will be repeated by the combination of the inner corner portions of the four meeting sections so that repetitions of the same pattern unit will be displayed indistinguishably in each individual pattern unit composing the corners of the rug and in the composite pattern unit afforded by the meeting edges of the sections across the lines of stitching so that the ribs at the meeting edges in the composite pattern unit will correspond in width with interior rib constituents of the individual pattern units.

STANLEY E. WAITE.
